UNITED STATES PATENT OFFICE.

FRANK C. GREENE, OF CLEVELAND, OHIO.

CAR-DUMPING MECHANISM.

976,170.

Specification of Letters Patent. Patented Nov. 22, 1910.

Application filed February 1, 1908. Serial No. 418,725.

To all whom it may concern:

Be it known that I, FRANK C. GREENE, citizen of the United States, resident of Cleveland, county of Cuyahoga, and State 5 of Ohio, have invented a new and useful Improvement in Car-Dumping Mechanisms, of which the following is a specification, the principle of the invention being herein explained and the best mode in which I have 10 contemplated applying that principle so as to distinguish it from other inventions.

The present invention relates to car dumping mechanism and is particularly designed for use in connection with the dumping of 15 mine cars such as are employed in coal mines and the like. Such mechanism is designed still more particularly for use in conjunction with a superposed track system, that is, a system in which the loaded car is received 20 on one track, dumped, and then discharged onto another track below such first track. It is unnecessary here to dilate upon the advantages, such as saving of space and the like, to be had by thus arranging the tracks. 25 There have been numerous difficulties, however, encountered in designing a dumping mechanism that will work easily and effectively in the situation thus presented. In a co-pending application, filed August 15, 30 1908, Serial No. 330,652, I have broadly set forth a type of dumping device invented by me whereby many of these difficulties are obviated.

The present structure is but another specific form of the invention there generally set forth, and has as its object, among other things, the adaptation of the device to power operation whereby at least certain of the movements may be positively effected and 40 controlled, as also the provision of means whereby the car may be shaken or jarred to facilitate the discharge of its contents when in the dumping position. Incidentally, but directly co-operative with the dumping mechanism, there is shown a car spotter, that is, a device for controlling the feeding of the cars onto such mechanism.

To the accomplishment of the above and related objects, said invention, then, consists 50 of the means hereinafter fully described and particularly pointed out in the claims.

The annexed drawings and the following description set forth in detail certain mechanism embodying the invention, such disclosed means constituting, however, but one

of various mechanical forms in which the principle of the invention may be used.

In said annexed drawings: Figure 1 is a front end elevation of a dumping mechanism wherein the several improvements referred 60 to above have been incorporated, such mechanism being designed primarily for use in dumping cars of the kind employed in coal mines of the anthracite region; Fig. 2 is a part section and part side elevation of the same, 65 showing in connection therewith, the car spotter, or feeding device, above referred to, as also contiguous portions of the two superposed tracks with which such dumping mechanism stands in operative relation; in 70 such Fig. 2 the device is shown in its initial operative position; and Figs. 3, 4 and 5 illustrate in similar part section and side elevation successive operative positions of the device wherein the car, received in the position shown in Fig. 2, is dumped and finally 75 discharged onto the lower, or car discharge, track.

The main operative element of the device is a floating track section A that is supported, in a manner presently to be set forth, in a vertically disposed framework B consisting preferably of two plates b arranged one on each side of the track section, and provided on their respective inner faces with 80 two guide-ways, B' B² in which are held 85 rollers or guide-wheels a mounted on the ends of transverse shafts a' constituting fixed elements in the track-section aforesaid. The guide-ways B' B² are conveniently 90 formed by securing appropriately bent sections b' of angle iron to the inner faces of the plates b and corresponding sets of such ways are respectively adapted to engage the two sets of guide rollers previously referred to. Such guide-ways intersect at 95 their upper ends and thence curve downward in forwardly, concave fashion with respect to the direction of discharge. In the intersecting portion of the ways there is located a pivotally mounted latch b² movable to close such portion against either way. The rearmost way is formed on the arc of a circle having the lower end of the other way as its center, and is furthermore provided with a branch B³ extending rearwardly and upwardly to a point just a trifle above the upper end of such other way. The form of the curve of the foremost way B' is determined by the direction of such 110

- branch B³ of the rearmost way, and by the relative rates of movement which it is desired to impart to the respective ends of the track section A, in the course of the latter's 5 reciprocation, such movement being obviously controlled by the ways, the construction of which has just been described. When held with guide rolls a in the respective upper ends of the corresponding guide ways, 10 the track section A is designed to be in alinement with the end of the upper car delivery track C and to incline forwardly and downwardly at substantially the same angle. Similarly, when in its lowermost position, 15 such track-section is designed to be alined with the lower car-discharge track C', the relative elevations of the lower ends of the two guide ways being determined with this in view.
- 20 For the purpose of imparting to the track-section the necessary vertical movement to thus position the same alternately in register with the upper and lower of the two superposed tracks, power means are provided. These means in the case in hand consist of a vertically disposed fluid-pressure cylinder D connected with a suitable source of fluid-pressure supply, preferably steam or compressed air. Assuming steam to be 25 thus employed, the live steam is led from a supply pipe d through one or the other of pipes d' d² to the top or bottom end of the cylinder D, the control being had by means of an operating valve D' located beneath 30 the operator's platform D² and adapted to be actuated by a suitable handle d³. The construction of valve D' is such that when one end of the cylinder is connected with the steam supply pipe d, the other end is 35 connected with an exhaust pipe d⁴.
- Associated with power-cylinder D, and alined therewith transversely of track-section A, are two other cylinders D³, one on each side of such cylinder D, such cylinders 40 D³ constituting means independent of said power means for regulating the reciprocation of the track-section. To this end, such cylinders D³ are filled with a suitable liquid such as dead oil, the flow of which from one 45 end to the other is regulated by a manually operable valve d⁵ in a common pass-pipe d⁶, thereby regulating the movement of the pistons d⁷ reciprocably mounted in the cylinders. The upper ends of such pistons d⁷ together with the upper end of the piston d⁸ 50 reciprocable in power cylinder D are jointed to a common cross-head D⁴ that is steadied by having its ends provided with rollers d⁹ held in vertical guides b⁸ similar to those 55 wherein rollers a are guided. Cross-head D⁴ is connected with a transverse shaft A², fixed to track-section A between guide shafts a', by means of connecting rods or links D⁵ 60 that are not only thus reciprocable with the 65 pistons as the latter move up and down, but

is adapted to oscillate with respect to such pistons as the track-section is tilted first in one direction and then the other by the guides B' B² between which it is held.

In order to retain the car upon the track-section pending the latter's downward tilting movement during the dumping operation, the forward end of such track-section is provided with a stop, or buffer, a², consisting simply of the upturned ends of the rails or 75 angle irons, constituting the rails of the section, suitably braced to withstand the strain. In order to minimize the shock that would otherwise be occasioned, both the dumping mechanism and the car, were the latter allowed to bump directly into this fixed stop as it is received onto the track section from the inclined car delivery track C, a resiliently supported secondary stop A' is provided wherewith such car has prior engagement. A preferred construction of this secondary stop embodies two dogs a⁵ pivotally mounted upon the forward ends of transverse shafts a' and so disposed and formed as to 80 engage the axle of the car as the wheels pass 85 along the track section. A rod q³ pivotally connected to each of such dogs and to the shaft A² to which the connecting rods D⁵ between the track section and reciprocable pistons d⁷ d⁸ are pivoted, together with an 90 interposed spring a⁴, serves to normally position such dog so that the engagement in question takes place just before the car engages the fixed stop a².

Reference has hereinbefore been made to 100 the relationship of floating track-section A to upper car-delivery track C as though such track-section registered directly with the same, just as in fact it does with lower car-discharge track C'. In the device as illustrated, however, and ordinarily when in use, it is proposed to employ in connection with the car-delivery track a car spotter, that is, a device for controlling the passage of cars along such track so as automatically to place 105 successive cars in position to be received onto the dumping mechanism proper. This car spotting device is accordingly interposed between the track and the dumping station and in the form illustrated comprises simply a 110 tilting track-section E supported on a transverse shaft e. Track-section E is bent in a vertical plane so as to present two portions e' e² respectively adapted in different positions of the section to register with track C and with floating track-section A. When portion e² is thus in register with track-section A, portion e' is raised sufficiently to act as a stop, preventing the entrance of a car thereon. Similarly, a car after being received onto tilting section E is normally prevented from being discharged onto section A by horns e³ mounted upon longitudinally disposed resiliently supported, rock-shafts e⁴ 115 and adapted to engage in the case in hand 120

the car axle, although, obviously, if found desirable they can just as well be arranged to engage the wheels of the car. Springs e^5 serve to thus normally position horns e^3 to 5 act as stops, while arms e^6 extend inwardly and are so disposed as to be engaged by the rear end of floating track-section A, as the latter finally comes into its full raised position, the effect of such engagement being to 10 depress the horns and allow the car to move onto the dump. Celerity in such movement is secured by the additional inclination attained by having track-section E bent in the manner previously described.

15 In the device as shown the track-section A is likewise effective to tilt the section E into its discharge position. If desired, however, this movement may be anticipated by so shifting the axis e of the tilting track-section 20 as to permit the weight of a loaded car, when received thereon, to overbalance the same, thereby leaving the horns e^3 alone to be operated by the track-section A.

The operation of the dump should be 25 readily apparent from the several illustrative views showing successive positions thereof. Thus, in Fig. 2, the car is just being received upon the track-section from the upper C of the superposed tracks. Upon now 30 relieving the pressure in the power cylinder D, floating track-section A begins to sink, such movement being controlled by proper regulation of the supply of steam to such cylinder, as also by the retarding effect of 35 cylinders D^3 which can be varied by adjustment of valve d^5 . Upon thus being depressed the forward shaft a' of the track-section is guided downwardly and forwardly until the rolls a borne upon its ends rest on 40 the lower ends of the corresponding guide-ways B' , the rolls upon the rear shaft passing, incidentally to such movement, from within the branched portion B^3 of the rear guide-way B^2 , full into such guide-way B^2 , 45 Fig. 3. From this initial dumping position, the car is adapted to be tilted into a still more sharply inclined position by simply increasing the pressure within the power-cylinder D, whereupon the track-section is 50 tilted about the forward shaft as an axis until the guide rolls borne by the rear shaft rest against the upper ends of the corresponding guide-ways, Fig. 4. In order to 55 facilitate the discharge of the car's contents, the track-section may be oscillated back and forth through a short arc with such degree of violence as will be necessary to discharge the coal from the car, such oscillation being secured by admitting the proper amount of 60 steam into the power cylinder as will be readily understood. When the car is finally emptied, the pressure within the power cylinder is again relieved, so as to permit the rear end of the track-section to swing down- 65 wardly until the rolls borne by the rear shaft

rest in the lower ends of the corresponding rear guide-ways. In this position the track-section inclines rearwardly and registers with the lower of the two superposed tracks, the degree of such inclination being sufficient 70 to cause the car to move promptly off onto the track. The tendency of the resiliently supported secondary stop A' will obviously be to help start the car upon this discharge movement. The position of the parts at the 75 conclusion of the discharge movement is shown in Fig. 5. Upon pressure being again supplied to the power cylinder, the movements just described are reversed and the whole track-section is elevated and the 80 shafts with the guide rolls restored to their normal positions in which the track registers with the upper track-section.

The operation of the spotting device, automatically effected as it is by the several 85 movements of the floating track-section, just described, occurs simultaneously with such movements and need not be further noticed since the correlation between the operation of the two devices should be sufficiently clear 90 already.

Obviously the mechanism just described is equally adaptable to the simple transfer of cars, either empty or loaded, from one superposed track to another, in which event 95 the angle of intermediate inclination, pending movement of the track-section from register with one to the other of the tracks C C', would not be made so steep as to disturb the contents of the car. The track-section, 100 furthermore, being power actuated may be reversed in its operation to raise cars from the lower to the upper track, if desired, and incidentally dump the same. Moreover, as to the car spotting device this is susceptible 105 of advantageous use in connection not only with the present specific form of dumping mechanism but also in conjunction with any movable track-section designed to receive 110 cars one by one from a fixed car-delivery track; or, indeed, simply to control the passage of the cars from one portion to another of a discontinuous track.

Other modes of applying the principle of my invention may be employed instead of 115 the one explained, change being made as regards the mechanism herein disclosed, provided the means stated by any of the following claims or the equivalent of such stated means be employed.

I therefore particularly point out and distinctly claim as my invention:

1. In mechanism of the class described, the combination of a reciprocable member, a member oscillatorily connected therewith, a floating track-section oscillatorily mounted upon said last-named member, and means adapted to oscillate said track-section upon reciprocation of said first member.

2. In mechanism of the class described,

the combination of a reciprocable member, a member oscillatorily connected therewith, a floating track-section oscillatorily mounted upon said last-named member, and means 5 adapted to independently control the movement of the respective ends of said track-section upon reciprocation of said first member.

3. In mechanism of the class described, 10 the combination of a reciprocable member, a member oscillatorily connected therewith, a track-section oscillatorily mounted upon said last-named member, and a relatively fixed guide-way engaging said track-section 15 and adapted to oscillate the same upon reciprocation of said first member, said track-section being at all times unsupported other than by said last-named member and said guide-way.

20 4. In mechanism of the class described, the combination of a reciprocable member, a member oscillatorily connected therewith, a track-section pivotally mounted upon said last-named member, and two relatively fixed 25 guide-ways respectively engaging said track-section at points on opposite sides of its pivotal axis and adapted to oscillate the same upon reciprocation of said first member.

30 5. In mechanism of the class described, the combination of a reciprocable member, a member oscillatorily connected therewith, a track-section pivotally mounted upon said last-named member, and corresponding 35 guide-means on each side of said track-section, each such means including two ways respectively engaging said track-section on opposite sides of its pivotal axis and curved in a forwardly concave fashion with respect 40 to the direction of discharge.

6. In mechanism of the class described, the combination of a reciprocable member, a member oscillatorily connected therewith, a track-section pivotally mounted upon said 45 last-named member, and corresponding guide-means on each side of said track-section, each such means including two ways respectively engaging said track-section on opposite sides of its pivotal axis and curved 50 in a forwardly concave fashion with respect to the direction of discharge, the rear-most way being provided with a rearwardly extending branch.

7. In mechanism of the class described, 55 the combination of a reciprocable member, a member oscillatorily connected therewith, a track-section pivotally mounted upon said last-named member, and corresponding guide-means on each side of said track-section, each such means including two ways respectively engaging said track-section on opposite sides of its pivotal axis and curved 60 in a forwardly concave fashion with respect to the direction of discharge, the rear-most 65 way being formed on the arc of a circle hav-

ing the lower end of the other way as its center and being provided with a branch extending rearwardly and upwardly to a point substantially on a level with the upper end of such other way.

8. In mechanism of the class described, 70 the combination of a reciprocable member, a member oscillatorily connected therewith, a track-section pivotally mounted upon said last-named member, and corresponding 75 guide-means on each side of said track-section, each such means including two ways respectively engaging said track-section on opposite sides of its pivotal axis, said ways intersecting at their upper ends and thence 80 curving downward in a forwardly concave fashion with respect to the direction of discharge, the rearmost way being provided with a rearwardly extending branch.

9. In mechanism of the class described, 85 the combination of a reciprocable member, a member oscillatorily connected therewith, a track-section pivotally mounted upon said last-named member, and corresponding 90 guide-means on each side of said track-section, each such means including two ways respectively engaging said track-section on opposite sides of its pivotal axis, said ways intersecting at their upper ends and thence 95 curving downward in a forwardly concave fashion with respect to the direction of discharge, the rearmost way being provided with a rearwardly extending branch, and a latch movable in the intersecting portion 100 of such ways to close such portion against either way.

10. In mechanism of the class described, the combination of a reciprocable member, a member oscillatorily connected therewith, a track-section pivotally mounted upon said 105 last-named member, and corresponding guide-means on each side of said track-section, each such means including two ways respectively engaging said track-section on opposite sides of its pivotal axis, said ways 110 intersecting at their upper ends and thence curving downward in a forwardly concave fashion with respect to the direction of discharge, the rearmost way being formed on the arc of a circle having the lower end of 115 the other way as its center and being provided with a branch extending rearwardly and upwardly to a point substantially on a level with the upper end of such other way, and a pivotally mounted latch movable 120 in the intersecting portion of such ways to close such portion against either way.

11. In mechanism of the class described, the combination of a reciprocable member, power means for reciprocating the same, and 125 a floating track-section oscillatorily mounted upon said member and bodily reciprocable therewith.

12. In mechanism of the class described, 130 the combination of a reciprocable member,

- power means for reciprocating the same, a floating track-section oscillatorily mounted upon said member and bodily reciprocable therewith, and means adapted to oscillate said track-section upon reciprocation of said member.
13. In mechanism of the class described, the combination of a reciprocable member, power means for reciprocating the same, a floating track-section oscillatorily mounted upon said member and bodily reciprocable therewith, and a relatively fixed guide-way engaging said track-section and adapted to oscillate the same pending the reciprocation of said member.
14. In mechanism of the class described, the combination of a reciprocable member, power means for reciprocating the same, a track-section oscillatorily mounted upon said member, and two relatively fixed guide-ways respectively engaging said track-section at points located on opposite sides of its pivotal axis.
15. In mechanism of the class described, the combination of a vertically disposed fluid-pressure actuated piston, a track-section oscillatorily supported thereby, and corresponding guide-means on each side of said track-section, each such means including two ways respectively engaging said track-section on opposite sides of its pivotal axis and curved in a forwardly concave fashion with respect to the direction of discharge.
16. In mechanism of the class described, the combination of a vertically disposed fluid-pressure actuated piston, a track-section oscillatorily supported thereby, and corresponding guide-means on each side of said track-section, each such means including two ways respectively engaging said track-section on opposite sides of its pivotal axis and curved in a forwardly concave fashion with respect to the direction of discharge, the rearmost way being provided with a rearwardly extending branch.
17. In mechanism of the class described, the combination of a vertically disposed fluid-pressure actuated piston, a track-section oscillatorily supported thereby, and corresponding guide-means on each side of said track-section, each such means including two ways respectively engaging said track-section on opposite sides of its pivotal axis and curved in a forwardly concave fashion with respect to the direction of discharge, the rear-most way being formed on the arc of a circle having the lower end of the other way as its center and being provided with a branch extending rearwardly and upwardly to a point substantially on a level with the upper end of such other way.
18. In mechanism of the class described, the combination of a vertically disposed fluid-pressure actuated piston, a member os-
- cillatorily connected with said piston, and a floating track-section borne by said member.
19. In mechanism of the class described, the combination of a vertically disposed fluid-pressure cylinder, a piston reciprocable therein, a member oscillatorily connected with said piston, and a floating track-section oscillatorily mounted upon said member.
20. In mechanism of the class described, the combination of a stationary vertically disposed fluid-pressure cylinder, a piston reciprocable therein, a member oscillatorily connected with said piston, a floating track-section pivotally mounted upon said member, and means adapted to oscillate said track-section upon reciprocation of said piston.
21. In mechanism of the class described, the combination of a vertically disposed fluid-pressure actuated piston, a member oscillatorily connected therewith, a track-section pivotally mounted upon said member, and means adapted to independently control the movement of the respective ends of said track-section upon reciprocation of said piston.
22. In mechanism of the class described, the combination of a vertically disposed fluid-pressure actuated piston, a member oscillatorily connected therewith, a track-section pivotally mounted upon said member, and a relatively fixed guide-way engaging said track-section and adapted to oscillate the same upon reciprocation of said piston.
23. In mechanism of the class described, the combination of a fixed, vertically disposed fluid-pressure cylinder, a piston adapted to be reciprocated thereby, a member oscillatorily connected with said piston, a track-section pivotally mounted upon said member, and two relatively fixed guide-ways respectively engaging said track-section on opposite sides of its pivotal axis and adapted to oscillate the same upon reciprocation of said piston.
24. In mechanism of the class described, the combination of a fixed, vertically disposed fluid-pressure cylinder, a piston adapted to be reciprocated thereby, a member oscillatorily connected with said piston, a track-section pivotally mounted upon said member, and corresponding guide-means on each side of said track-section, each such means including two ways respectively engaging said track-section on opposite sides of its pivotal axis and curved in a forwardly concave fashion with respect to the direction of discharge.
25. In mechanism of the class described, the combination of a fixed, vertically disposed fluid-pressure cylinder, a piston adapted to be reciprocated thereby, a member oscillatorily connected with said piston, a track-section pivotally mounted upon said member, and corresponding guide-means on each side of said track-section, each such means including two ways respectively engaging said track-section on opposite sides of its pivotal axis and curved in a forwardly concave fashion with respect to the direction of discharge.

- each side of said track-section, each such means including two ways respectively engaging said track-section on opposite sides of its pivotal axis and curved in a forwardly 5 concave fashion with respect to the direction of discharge, the rearmost way being provided with a rearwardly extending branch.
26. In mechanism of the class described, the combination of a fixed, vertically disposed 10 fluid-pressure cylinder, a piston adapted to be reciprocated thereby, a member oscillatorily connected with said piston, a track-section pivotally mounted upon said member, and corresponding guide-means on 15 each side of said track-section, each such means including two ways respectively engaging said track-section on opposite sides of its pivotal axis and curved in a forwardly concave fashion with respect to the 20 direction of discharge, the rear-most way being formed on the arc of a circle having the lower end of the other way as its center and being provided with a branch extending rearwardly and upwardly to a point substantially 25 on a level with the upper end of such other way.
27. In car-dumping mechanism, the combination of two superposed tracks respectively inclining toward and from the dumping 30 station, a vertically reciprocable member, power means for reciprocating the same, and a track-section oscillatorily mounted upon said member and reciprocable therewith into register with either of said tracks 35 as desired.
28. In car-dumping mechanism, the combination of two superposed tracks respectively inclining toward and from the dumping 40 station, a vertically reciprocable member, power means for reciprocating the same, a track-section oscillatorily mounted upon said member and reciprocable therewith into register with either of said tracks as desired, and means adapted to oscillate said 45 track-section upon such reciprocation into corresponding inclination with said tracks.
29. In car-dumping mechanism, the combination of two superposed tracks, the upper inclining toward, the lower from, the dumping 50 station, a vertically disposed fluid-pressure actuated piston, a member oscillatorily connected with said piston, a track-section pivotally mounted upon said member and movable therewith into register with either 55 of said tracks as desired, and corresponding guide-means on each side of said track-section, each such means including two ways respectively engaging said track-section on opposite sides of its pivotal axis and curved 60 in a forwardly concave fashion with respect to the direction of discharge.
30. In mechanism of the class described, the combination with a discontinuous track, of means for controlling the passage of cars 65 therealong, such means comprising an inter-
- posed tilting track-section adapted in one position to receive a car from one portion of said track and in another position to discharge such car onto the other portion thereof, said track-section serving, when in such last-named position, as a stop for cars on such first track portion, and an independently operable stop on said track-section for controlling the discharge of a car therefrom.
31. In mechanism of the class described, 70 the combination of a car-delivery track, a movable track-section, and means for controlling the passage of cars from said track to said track-section, said means comprising an interposed tilting track-section itself 80 capable of holding a car and adapted in one position to receive such a car from said track and in another to discharge the same onto said first track-section, said tilting track-section serving, when in such last-named position, as a stop for cars on said track.
32. In mechanism of the class described, 85 the combination of a car-delivery track, a movable track-section, and means for controlling the passage of cars from said track to said track-section, said means comprising an interposed tilting track-section adapted in one position to receive a car from said track and in another to discharge the same 90 onto said first track-section, said tilting track-section serving, when in such last-named position, as a stop for cars on said track, and means controlling the discharge of a car from said tilting track-section.
33. In mechanism of the class described, 95 the combination of a car-delivery track, a movable track-section, and means for controlling the passage of cars from said track to said track-section, said means comprising 100 an interposed tilting track-section adapted in one position to receive a car from said track and in another to discharge the same onto said first track-section, said tilting track-section serving, when in such last-named position, as a stop for cars on said track, and an independently operable stop on said tilting track-section for controlling the discharge of a car therefrom.
34. In mechanism of the class described, 105 the combination of a car-delivery track, a movable track-section, and means for controlling the passage of cars from said track to said track-section, said means comprising 110 an interposed tilting track-section adapted in one position to receive a car from said track and in another to discharge the same onto said first track-section, said tilting track-section serving, when in such last-named position, as a stop for cars on said track, and means controlling the discharge of a car from said tilting track-section.
35. In mechanism of the class described, 115 the combination of a car-delivery track, a movable track-section, and means for controlling the passage of cars from said track to said track-section, said means comprising 120 an interposed tilting track-section adapted in one position to receive a car from said track and in another to discharge the same onto said first track-section, said tilting track-section serving, when in such last-named position, as a stop for cars on said track, and means controlling the discharge of a car from said tilting track-section, operation of said stop being correlated with the movement of said first track-section.
36. In mechanism of the class described, 125 the combination of a car-delivery track, a movable track-section, and means for controlling the passage of cars from said track to said track-section, said means comprising 130 an interposed tilting track-section adapted in one position to receive a car from said track and in another to discharge the same onto said first track-section, said tilting track-section serving, when in such last-named position, as a stop for cars on said track, and means controlling the discharge of a car from said tilting track-section.

the combination of a car-delivery track, a movable track-section, and means for controlling the passage of cars from said track to said track-section, said means comprising
 5 an interposed tilting track-section adapted in one position to receive a car from said track and in another to discharge the same onto said first track-section, said tilting track-section serving, when in such last
 10 named position, as a stop for cars on said track, and a stop on said tilting track-section normally operative to prevent the discharge of a car therefrom, said first track-section being effective to render said stop
 15 inoperative on coming into register with said tilting track-section.

36. In mechanism of the class described, the combination of a car-delivery track, a movable track-section, and means for controlling the passage of cars from said track to said track-section, said means comprising an interposed tilting track-section itself capable of holding a car and adapted in normal position to receive such a car from
 20 said track and in another position to discharge a car onto said first track-section, the latter being adapted to move said tilting track-section into such second position upon coming into register therewith, and said
 25 tilting track-section serving, when in such second position, as a stop for cars on said track.

37. In mechanism of the class described, the combination of a car-delivery track, a movable track-section, and means for controlling the passage of cars from said track to said track-section, said means comprising an interposed tilting track-section adapted in normal position to receive a car from said
 30 track and in another position to discharge a car onto said first track-section, said tilting track-section serving, when in such second position, as a stop for cars on said track, and an independently operable stop on said
 35 tilting track-section normally operative to prevent the discharge of a car therefrom, said first track-section being simultaneously effective, on coming into register with said
 40 tilting track-section, to move the same into its second position and to render said stop
 45 inoperative.

38. In mechanism of the class described, the combination of a reciprocable member, power means for reciprocating the same, a

track-section oscillatorily mounted upon 55 said member and reciprocable therewith, and means independent of said power means for regulating the reciprocation of said member.

39. In mechanism of the class described, the combination of a reciprocable member, 60 power means for reciprocating the same, a track-section oscillatorily mounted upon said member and reciprocable therewith, and automatic retarding means adapted to regulate the reciprocation of said member 65 independently of said power means.

40. In mechanism of the class described, the combination of a reciprocable member, power means for reciprocating the same, a track-section oscillatorily mounted upon said 70 member and bodily reciprocable therewith, and means regulating the reciprocation of said member.

41. In mechanism of the class described, the combination of a reciprocable member, 75 power means for reciprocating the same, a track-section oscillatorily mounted upon said member and bodily reciprocable therewith, and automatic retarding means adapted to regulate the reciprocation of said 80 member.

42. In mechanism of the class described, the combination of a plurality of aligned cylinders, piston rods reciprocable therein, respectively, a track-section oscillatorily 85 mounted upon said piston rods, fluid-pressure connections for one of said cylinders, another of said cylinders containing a liquid, and a pass-pipe connecting the ends of such other cylinder, whereby movement of the 90 piston therein is regulated.

43. In mechanism of the class described, the combination of three aligned cylinders, piston rods reciprocable therein, respectively, a common cross-head for said piston 95 rods, a track-section oscillatorily mounted upon said cross-head, fluid-pressure connections for the intermediate of said cylinders, and a common pass-pipe for the two outer cylinders whereby movement of the pistons 100 therein is regulated.

Signed by me this 28th day of January, 1908.

FRANK C. GREENE.
